UNITED STATES PATENT OFFICE.

CHARLES T. KINSMAN, OF WILLIAMSTOWN, MASSACHUSETTS.

ROOT-CANAL FILLING FOR TEETH.

SPECIFICATION forming part of Letters Patent No. 674,419, dated May 21, 1901.

Application filed March 9, 1901. Serial No. 50,495. (No model.)

To all whom it may concern:

Be it known that I, CHARLES T. KINSMAN, a citizen of the United States, residing at Williamstown, in the county of Berkshire and State of Massachusetts, have invented certain new and useful Improvements in Root-Canal Filling for Teeth; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in root-canal fillings for teeth; and it consists of a central pin of stiff non-corrodible metal or alloy around which is a compound composed of gutta-percha, zinc 10 oxid, and yellow resin, the gutta-percha compound being made to cling tightly to the pin by first roughening the latter by forming small barbs which are coated with the compound in solution, which afterward is allowed to harden. The fillings being thus prepared may be easily forced in the minute root cavities after the removal of the dental pulp.

Heretofore it has been common in the art to employ gutta-percha points consisting of 20 tapering sticks of gutta-percha, in combination with oxid of zinc or some similar material; but owing to their containing no stiffening except that of the compound itself, and when softened by heat or solvents to enable 30 them to spread in the root cavities, completely filling the latter, they are too soft to follow narrow or crooked canals. If the fillings are not softened, they do not completely fill the canal, and therefore do not accomplish the 35 purpose for which a root-canal filling is intended.

The object of this invention is to obviate these defects and to produce fillings which cannot double upon themselves or crush together while being inserted in any shape or size of canal, as the metal is made small enough to enter the smallest canals and stiff enough to follow them and will carry sufficient gutta-percha compound to completely 45 fill the canal, regardless of its shape, the ex-

cess of the compound being easily pressed back out of the canal and removed.

Owing to the strength of my improved fillings, they may be easily removed, whereas cement or small gutta-percha fillings are difficult to remove.

My invention is clearly illustrated in the accompanying drawings, which, with the letters of reference marked thereon, form a part of this application, and in which—

Figure 1 is an enlarged perspective view of one of my root-fillings for teeth. Fig. 2 is a central longitudinal section through one of the fillings, said filling also very much enlarged. Fig. 3 is a view of the central rigid 65 metallic portion of the filling.

Reference now being had to the details of the drawings by letter, A designates the central skeleton of the filling, made, preferably, of any suitable non-corrodible metal or alloy, 70 and its circumference is roughened by forming short barbs B, whereby when the compound of gutta-percha, zinc oxid, and yellow resin is applied thereto and allowed to harden it will cling tightly thereto, and when the filling is inserted in the root-canals it will follow the minute and crooked canals, and if for any purpose it is desired to remove the filling it may be easily done, owing to the rigid nature 75 of the filling.

In placing the filling the same should be slightly larger than the size of the canal, and after the filling has been warmed gently over a flame it should be dipped in some antiseptic oil to lubricate the filling, after which it 80 should be pressed gently in place.

Having thus described my invention, what I claim to be new, and desire to secure by Letters Patent, is—

A root-canal filling for teeth, consisting of 90 a central metallic skeleton coated with a compound of gutta-percha, zinc oxid and yellow resin, as set forth.

In testimony whereof I hereunto affix my signature in presence of two witnesses.

CHARLES T. KINSMAN.
